JACK

Darcy D. Knox, Center Ossipee, N. H.

Application September 16, 1932
Serial No. 633,508

5 Claims. (Cl. 272—70.1)

This invention relates to jacks for masons, painters, carpenters, and other workmen and has for an object to provide a jack which may be worn on the feet in pairs when working on low ceilings and walls at places inaccessible but not quite high enough to warrant building a staging.

A further object is to provide a jack of this type which will be light, strong and durable, will be worn with comfort, and may be applied and removed in minimum time and with minimum effort.

A further object is to provide a staging jack which will have the foot plate adjustably mounted so that the foot plate may be raised or lowered, as desired, and may be locked in each adjusted position.

With the above and other objects in view the invention consists in certain novel details of construction and combinations of parts hereinafter fully described and claimed it being understood that various modifications may be resorted to within the scope of the appended claims without departing from the spirit or sacrificing any of the advantages of the invention.

25 In the accompanying drawing forming part of this specification,

Figure 1 is a perspective view showing the jack in use,

Figure 2 is a plan view of the jack,

30 Figure 3 is a side elevation of the jack,

Figure 4 is a cross section taken on the line 4—4 of Figure 2, and

Figure 5 is a detail cross section taken on the line 5—5 showing the adjusting means.

35 Referring now to the drawing in which like characters of reference designate similar parts in the various views, 10 designates a substantially oval base plate at the bottom of which is attached a pair of longitudinal runners 11 which 40 preferably are formed of strap metal bent to provide flat treads 12, the strap metal being bent up at the ends and inclined inwardly to provide front and rear risers 13 and 14. The risers of both runners are riveted to the ends of the base 45 plate, as shown at 15.

Diagonal strap braces 16 are riveted to the treads, as shown at 17, and are riveted to the sides of the base plate, as shown at 18. The diagonal braces are riveted together, as shown 50 at 19, at their intersection. The diagonal braces are also formed of strap metal and support the runners against collapse and at the same time yield sufficiently to permit the runners yielding so that the device may be comfortably worn due 55 to this spring effect as the weight of the wearer

is lifted and lowered on the jack while stepping.

A sole plate 20, of substantially the same shape as the sole of a shoe, is supported upon the base plate preferably by means of three pins 21, a pair of the pins being arranged at the toe portion of the plate 20 and a third pin being disposed at the heel portion of the plate 20. These pins are preferably formed integral with the sole plate and extend downwardly from the bottom thereof.

As best shown in Figure 5, bosses 22 are formed integral with the bottom of the base plate 10 and are perforated, as is also the base plate, as shown at 23 and 24, respectively, to slidably receive the pins 21. A set screw 25 is threaded 65 through the side of each boss and bears against the corresponding pin. Loosening of the set screw permits of the pin being raised or lowered to correspondingly adjust the sole plate whereupon the set screw may be tightened to hold 70 the sole plate in each adjusted position.

A toe strap 26, preferably formed of two pieces of leather and riveted, as shown at 27, to the sole plate, is laced together, as shown at 28, to comfortably enclose the toe of the wearer's shoe 80 and hold the jack firmly in place on the shoe. The strap is of sufficient width to maintain firm engagement with the shoe and at the same time allow the shoe to be slid in or out in minimum time and with minimum effort so that the jack 85 may be applied or removed in a jiffey.

From the above description it is thought that the construction and operation of my invention will be fully understood without further explanation.

90 What is claimed is:

1. A jack for workmen comprising a base plate, runners on the bottom side of the base plate, a sole plate, means for adjustably mounting the sole plate vertically on the base plate, 95 and means for securing the sole plate to the wearer's shoe.

2. A jack for workmen comprising a base plate, resilient runners having flat treads and having front and rear risers secured to the sole plate, 100 braces connecting the runners with the base plate, the braces being crossed and resilient, a sole plate superposed above the base plate, pins extending downwardly from the sole plate, means for adjustably securing the pins to the base 105 plate, and a strap carried by the sole plate for attaching the jack to the wearer's shoe.

3. A jack for workmen comprising a base plate, lugs on the underneath face of the base plate, 110 a sole plate, pins extending downwardly from

the sole plate and passing through the sole plate and the lugs, set screws threaded through the sides of the lugs and engaging the pins to hold the sole plate in each adjusted position, a toe strap carried by the sole plate, and longitudinal runners carried by the base plate.

4. A jack for workmen comprising a base plate, resilient runners having flat treads and having the ends curved upwardly and inclined inwardly 10 and riveted to the base plate, crossed braces riveted together at their crossing and having their ends riveted to the runners and to the base plate, said braces being resilient, there being openings in the base plate, bosses surrounding said 15 openings in the base plate, a sole plate, pins ex-

tending downwardly from the sole plate and passing through the openings in the base plate and extending through the bosses, set screws threaded through the sides of the bosses and engaging the pins for holding the sole plate in each 80 adjusted position, and a toe strap carried by the sole plate for strapping the jack on the wearer's shoe.

5. A jack for workmen comprising a base plate, resilient longitudinal runners on the bottom of 85 the base plate, a vertically adjustable sole plate carried by the base plate, and a toe strap carried by the sole plate for securing the jack to the wearer's shoe.
